GORILLA FIGURE TOY

Fred Kort, Los Angeles, Calif., assignor to Imperial Toy Corporation, Los Angeles, Calif.

Filed Apr. 11, 1973, Ser. No. 350,050

Term of patent 14 years

Int. Cl. D21—01

U.S. Cl. D34—2 R

FIG. 1

FIG. 2

FIG. 3

FIG. 4

FIG. 5

FIG. 1 is a front elevational view of a gorilla figure toy in a typical posture showing my new design;

FIG. 2 is a left-side elevational view, as seen from the right side of FIG. 1 showing my new design;

FIG. 3 is a right-side elevational view as seen from the left side of FIG. 1;

FIG. 4 is a top plan view showing my new design; and

FIG. 5 is a rear elevational view of my new design.

I claim:

The ornamental design for a gorilla figure toy, substantially as shown and described.
